UNITED STATES PATENT OFFICE.

HARRY RANDOLPH VAN DEVENTER, OF SUMTER, SOUTH CAROLINA, ASSIGNOR TO
SPLITDORF ELECTRICAL COMPANY, OF NEWARK, NEW JERSEY, A CORPORATION
OF NEW JERSEY.

IGNITION DEVICE.

1,327,361.

Specification of Letters Patent.

Patented Jan. 6, 1920.

Application filed October 13, 1917. Serial No. 196,371.

To all whom it may concern:

Be it known that I, HARRY R. VAN DEVENTER, a citizen of the United States, residing at Sumter, in the county of Sumter and 5 State of South Carolina, have invented certain new and useful Improvements in Ignition Devices, of which the following is a specification, reference being had to the accompanying drawing.

10 The invention relates to new and useful improvements in ignition devices, and more particularly to an ignition device including ignition electrodes, a generator electrically connected to the electrodes and a trip-operated spring-actuated device for said electrodes.

An object of the invention is to provide a two-part supporting bracket for an ignition device of the above character, wherein the 20 electrodes and the trip-operated spring-actuated mechanism for the generator and electrodes are carried by one part of the supporting bracket, while the generator alone is carried by the other part of the said 25 bracket.

A further object of the invention is to provide a supporting bracket of the above character, which is so constructed that the supporting part for the generator together 30 with the generator may be removed without disturbing the electrodes and the trip-operated spring-actuated mechanism, so that a battery may be used for supplying current to the electrodes for ignition.

35 A further object of the invention is to provide a supporting bracket for an ignition device of the above character which may be cheaply manufactured.

In the drawings which show by way of 40 illustration one embodiment of my invention,

Figure 1 is a side view of a supporting bracket embodying my improvements, with the generator, the electrodes and the spring-45 actuated mechanism therefor mounted thereon;

Fig. 2 is a front view of the same with the generator removed;

Fig. 3 is a plan view of the supporting 50 bracket with the generator, the electrodes and the actuating mechanism removed.

The invention broadly consists of an ignition device including a two-part supporting bracket. On one part of the supporting 55 bracket is mounted an ignition electrode and

the trip-operated spring mechanism which operates the generator, while on the other part of the bracket is the generator. The part of the bracket which supports the generator is carried by and projects from the 60 part of the bracket which supports the electrodes and the actuating mechanism. This permits the generator and the supporting part of the bracket therefor, to be readily removed in case the bracket is broken, or 65 when the generator is to be repaired and a battery used to supply current to the electrodes.

Referring more in detail to the drawings, my improved ignition device consists of a 70 two-part supporting bracket S. Said supporting bracket consists of the part 1, which is adapted to be attached to an engine cylinder by means of stud bolts passed through openings 3 and 4. Suitable nuts are threaded 75 on to these bolts and clamp said bracket against the engine cylinder. The part 1 of the bracket is provided with a sleeve 5, which projects through an opening in the cylinder wall into the cylinder. Mounted in this 80 sleeve 5 is a fixed electrode 6, and a movable electrode 7. The electrodes are provided with ignition points 8 and 9 respectively. The movable electrode 7 is provided with an arm 10, at its outer end. A spring 11 bears 85 at one end against said arm and its other end against an abutment 12; this spring shifts the movable electrode so as to normally hold the ignition points in contact.

Also mounted on the part 1 of the supporting bracket is the trip lever 13. Said bracket is provided with a rigid bearing 14, which carries the trip lever. Said trip lever is formed with pins 15 and 16. A spring 17 engages at one end the pin 15, and at its other end a pin 18, carried by the bracket part 1. The spring 19, engages at one end the pin 16, and at its other end pin 20, also carried by the bracket part 1. This trip lever is actuated by a trip finger 21, which is adapted to engage a shoulder 22, on the trip lever, moving the same so as to throw the spring out of alignment so that when the trip finger slips from the shoulder the trip lever will be turned in counter-clockwise direction. The trip lever is provided with a cam shoulder 23, which is adapted to engage the arm 10, so as to separate the electrodes and produce a spark, when said springs move the trip lever in the direction stated. 110

The bracket part 1, is formed with strengthening webs or ribs as clearly shown in the drawings, so as to provide a very rigid support for the spring-actuating mechanism. The lower portion of part 1, of the supporting bracket is faced and adapted to receive and support the projecting part 2 of said supporting bracket. The part 2 of the supporting bracket has a downwardly depending flange 24, which is provided with suitable openings to receive the bolts 25 and 26. These bolts are threaded into suitable openings in the supporting part 1 of the bracket. The supporting part 2, of the bracket is in form of a shelf on which the generator indicated at G rests. Suitable bolts 26, pass up through openings in the shelf and are threaded into the base of the generator.

20 The flux shifting member of the generator is provided with a forked arm which is adapted to engage the pin 15, so that the movements of the trip lever are imparted to the flux shifting member and thereby a current is generated for ignition. This flux shifting member is electrically connected to the ignition electrode.

From the above it will be apparent that I have provided a supporting bracket which is very strong and durable and which can be cheaply made. Part 1, may be of cast metal, while part 2, may be of either cast or stamped metal and readily attached to part 1. It will also be noted that not only the electrodes but the trip lever and actuating springs are carried by part 1 of the supporting bracket so that the supporting part 2 for the generator may be removed without interfering with the operation of the trip mechanism and the actuation of the movable electrode. This enables the generator and also the supporting shelf supporting the same to be temporarily removed and out of the way and at the same time current may be supplied from a battery for furnishing ignition. Then again, the projecting shelf which carries the heavy generator may be broken. By my improved construction the shelf may readily be replaced without necessitating the replacement of the entire supporting bracket. It will

also be noted that the electrodes and the actuating trip lever are all mounted on the integral supporting part 1, of the bracket and therefore the impact of the push rod 55 and the jar incident to the movement of the actuating springs do not in any way tend to loosen the nuts or bolts which support the shelf for the generator.

It is obvious that minor changes in the details of construction and also the arrangement of the parts may be made without departing from the spirit of the invention as set forth in the appended claims.

Having thus described my invention, what I claim as new, and desire to secure by Letters Patent, is:—

1. An ignition device comprising a two part supporting bracket, ignition electrodes carried by one part of said bracket, a generator carried by the other part of said bracket, and a trip operated spring actuating device for said generator and electrodes carried by the part of said bracket supporting the electrodes.

2. An ignition device comprising a two part supporting bracket, one of said parts being in the form of a shelf carried by and projecting from the other part of said bracket, a generator mounted on said shelf, a fixed and a movable electrode carried by the part of the bracket supporting the shelf, actuating devices for said generator and said movable electrode carried by the part of the bracket supporting the electrodes.

3. An ignition device comprising a two part supporting bracket, one of said parts being in the form of a shelf carried by and projecting from the other part of said bracket, a generator mounted on said shelf, a fixed and a movable electrode carried by the part of said bracket supporting the shelf, a trip lever and actuating springs therefor, carried by the part of the bracket supporting the electrodes, and means whereby said trip lever actuates the generator and movable electrode.

In testimony whereof I hereunto affix my signature.

HARRY RANDOLPH VAN DEVENTER.
